UNITED STATES PATENT OFFICE.

ROBERT T. DICKEY, OF DEL RIO, TEXAS.

AUTOMATIC FLOAT VALVE.

Application filed December 11, 1926. Serial No. 154,226.

The present invention relates to improvements in automatic float valves and has for its primary object to provide a valve having an auxiliary safety valve to insure closure of the valve casing.

A further object of the invention is the provision of an improved automatic float valve which will insure closure of the valve in the event of the operating float structure becoming inoperative.

Another object of the invention is the provision of a valve structure particularly adapted for controlling the delivery of water to a storage tank designed to automatically cut off the water supply when the tank has been filled to a pre-determined height.

Still another object of the invention is the provision of a valve of the above character which is comparatively simple and durable of construction and which can be manufactured at a relatively low cost.

Other objects and advantages of the invention will become apparent as the description progresses.

In the accompanying drawing forming a part of this specification and in which like reference characters are employed to designate corresponding parts throughout the same:

Figure 1 is a vertical sectional view taken through a portion of a storage tank and valve structure constructed in accordance with my invention,

Figure 2 is a top plan view of the valve structure, and

Figure 3 is a transverse sectional view taken on the line 3—3 of Figure 1.

Referring to the drawing, wherein for the purpose of illustration is shown the preferred embodiment of my invention, the numeral 10 generally designates a fragmentary portion of a storage tank adapted to contain water. Formed in the bottom of the tank 10 adjacent one end is an intake opening while an outlet opening (not shown) is formed in the side wall preferably at the opposite end.

The important characteristic of my invention resides in the provision of an automatically operable control valve connecting with a water feed line and disposed in the tank 10. This valve is arranged so as to automatically open when the water supply in the tank has been drained below a pre-determined level and to automatically close when water has been supplied to the tank to a suitable level. In carrying out my invention, I provide a

longitudinal valve casing 11 embodying an intermediate cylindrical casing 12. Formed at the lower end of the casing 12 and of slightly reduced diameter is an interiorly screw 60 threaded sleeve 13 forming the intake passage of the valve casing. The valve is normally arranged in a vertical position, the sleeve 13 being tightly fitted in the intake opening of the tank as illustrated and projecting downwardly below the tank bottom. A water supply pipe 14 is threadedly connected with the sleeve 13 as shown in Figure 1, the diameter of this pipe varying with the feed capacity of the valve. An essential feature 70 of my present construction, however, is the practical application of relatively large feed lines so as to permit rapid filling of the tank.

Formed at the upper end of the cylindrical casing 12 and of decreased diameter with respect to the cylindrical casing is an outlet sleeve 15, the lower end projecting slightly downward within the valve chamber to form a valve seat 16 while the upper end is formed with an annular re-inforcing flange 17. 80 From this description it is apparent that the intermediate portion of the valve casing is of materially increased diameter with respect to the intake and discharge passages, the purpose of which will become apparent as the 85 description progresses.

The inner side of the valve casing 11 carries an angular bracket 18, the lower horizontal arm being integrally connected with the side of the casing or secured thereto while the upper end of the vertical arm is bifurcated to form a bearing 19. Fulcrumed on the bracket 18 is an operating bar 20 formed so as to provide an upper horizontal extension 21 and a lower offset extension 22. The bar 20 is connected with the upper forked end of the bracket 18 by means of a pivot pin 23 extending transversely through openings in the bifurcated end of the bracket and through an opening in the upper extension 21 of the bar 20. One end of the fulcrumed bar 20 is therefore located above the valve casing 11 while the opposite end is disposed in a lowered position in the intermediate portion of the tank.

A connecting link 24 is formed so that its lower end pivotally connects with the end of the extension 22 of the fulcrumed bar while the upper end pivotally connects with an eye 25 secured to the lower face of a float 26. The float 26 may be of any preferred form designed to float on the surface of the liquid

to swing the fulcrum bar 20 and automatically actuate the valve structure.

Vertically movable with respect to the upper portion of the valve casing 11 is a valve head 27 including a flat circular body 28 formed with a convex projection 29 on its upper central portion. The convex projection is formed with a transversely extending groove 30. Formed on the lower face of the valve head 27 at the center thereof is a circular ring 31 defining a central recess 32. Rigidly secured to the lower edge of the ring 31 is a valve body 33, flat on its upper surface and convex on its lower surface. This valve body is formed so as to tightly seat on the upper end of the valve sleeve 15 and is secured to the valve head by screws 34 threadedly fitted in the ring 31. The center of the valve body is formed with a bore 35 aligning with the recess 32 formed in the center of the valve head.

Pivottally connected with the upper extension 21 of the fulcrumed arm 20 adjacent its outer end are a pair of links 36 arranged in parallel positions and extending downwardly into the groove 30 formed in the valve head. The lower ends of the links 36 are pivottally connected in the valve head by means of a transverse pivot pin 37 so that swinging movement of the fulcrumed arm will vertically reciprocate the valve head 27 and the body 33 to elevated open position or to a lowered closed position.

As previously indicated an important feature of my present invention comprises the provision of a double acting valve structure embodying the provision of a safety valve which will automatically close in the event of failure of the float mechanism to function. The safety valve embodies a valve rod 38 having a loop formed on its upper end embracing a transversely extending support pin 39. The pin 39 is tightly lodged in openings formed in the ring 31 to support the valve rod 38 in a suspended position. It is therefore apparent that the upper looped end of the valve rod 38 is supported within the recess 32 formed in the valve head while the lower portion extends downwardly and terminates in the intermediate portion of the body casing below the valve seat 16. Rigidly secured to the lower extremity of the valve rod 38 is a circular valve 40 the upper peripheral edge portion being disposed in a flat horizontal position to engage the lower end of the sleeve 15. A transversely mounted bracket 41 is secured in the intermediate portion of the sleeve 15, the central portion of the bracket being formed with an opening through which the valve rod 38 is extended to maintain the valve rod in a vertical position.

In operation, when the liquid contained in the tank is drained therefrom through the discharge opening of the tank, the float 26

level of the liquid. Due to the construction of the fulcrumed arm 20, the portion 22 of the arm will swing downwardly with the movement of the float so that the portion 21 will be elevated and the upper valve raised from its seat permitting the delivery of liquid through the valve and into the tank. The structure is arranged so that in the open position of the valve, the upper valve member will be sufficiently elevated to permit a free discharge of the liquid through the sleeve of the casing. The lower safety valve 40, will be also elevated simultaneously with the upward movement of the upper control valve, the lower safety valve being designed to normally terminate its upward movement substantially below the seat 16 of the sleeve 15 so as to permit the liquid to freely pass about the valve and through the discharge opening during the filling of the tank.

If, for any reason, the float operating mechanism which controls the movement of the upper control valve should become disconnected or inoperative the pressure of the water flowing through the valve casing will automatically force the lower safety valve 40 to its seat 16 and thereby close the valve and prevent the liquid overflowing the tank. This construction will obviate considerable waste in supplying water or other liquid to storage tanks of various types such as water feed troughs, flush tanks and the like wherein the operating mechanism becomes inoperative due to the sticking of the pivot structure or breakage of the component elements. Another advantage embodied in the present structure is the practicability of constructing valves of this type in relatively large sizes to accommodate supply pipes of large capacity.

It is to be understood that the form of my invention herewith shown and described is to be taken as the preferred example of the same and that various changes as to the shape, size and arrangement of parts may be resorted to without departing from the spirit of the invention or the scope of the subjoined claims.

Having thus described my invention, I claim:

1. A valve of the character described comprising a valve casing including an intermediate enlarged casing section, a reduced inner sleeve formed at one end of the valve casing engageable with an inlet feed pipe, and a reduced outlet sleeve formed at the opposite end of the valve casing having a valve seat formed at its exterior end and a second valve seat at its interior end, a control valve adapted to be seated upon the exterior valve seat, mechanism for operating the said control valve to a closed position on the valve seat and to an open position raised from the valve seat, a safety valve connected with the control valve including a valve rod pivotally connected with the control valve and extend-

ing within the valve casing, and a valve formed on the inner end of the valve rod, the said safety valve being arranged to normally remain unseated during the operation of the 5 control valve and operable by the pressure of a liquid passing through the valve to engage the inner valve seat when the control valve operating mechanism becomes inoperative.

2. An automatic valve comprising a vertical valve casing including an enlarged intermediate casing section, an inlet sleeve formed on the lower end of said section engageable with a supply pipe, and an outlet sleeve formed on the upper end of the section, a 15 valve seat formed at the upper extremity of the outlet sleeve, a second valve seat formed on the lower extremity of the outlet sleeve, a main control valve for engagement with the upper seat, means operatively associated with 20 the main control valve for automatically adjusting the position thereof, a safety valve including a valve rod pivotally connected with the main control valve and extending downwardly within the valve body and a valve 25 member secured to the lower extremity of the valve rod freely movable within the casing section of the body and movable simultaneously with the control valve and normally held out of contact with the lower seat and 30 arranged to engage the lower seat by the force of a liquid flowing through the valve when the main control valve operating structure fails to function.

3. An automatic valve comprising a casing formed with an intermediate enlarged casing section, an inlet sleeve formed at the lower end of said casing adapted for connection with a liquid supply pipe and an outlet sleeve formed at the upper end of the casing and having a valve seat formed on its upper edge 40 and a second valve seat formed on its lower edge; a control valve for engagement with the upper valve seat, means for adjusting the said valves with respect to its seat, a safety valve including a valve rod pivotally connected 45 with the control valve and a valve member secured to the lower end of the valve rod and normally suspended in the intermediate portion of the enlarged casing section and engageable with the inner valve seat, a bracket 50 secured to the side of the casing, an arm pivotally connected with the upper end of the bracket, a float connected with the inner end of the arm, links pivotally connecting the outer end of the arm and the control valve 55 whereby the control valve will be automatically opened and closed by the movement of the float, the said safety valve being vertically operable simultaneously with the movement of the control valve and normally maintained out of engagement with the seat and engageable with the inner seat by the pressure of the liquid when the control valve and adjusting means therefor fails to function. 60

In testimony whereof I affix my signature.
ROBERT T. DICKEY.
